[57] **CLAIM**

The ornamental design for a cutting board for adjustable bread knives, as shown and described.

DESCRIPTION

FIG. 1 is a perspective view of the invention;
FIG. 2 is a top plan view of the invention;
FIG. 3 is a left side elevation view of the invention; the right side being a mirror image thereof;
FIG. 4 is a front elevation view of the invention;
FIG. 5 is a rear elevation view of the invention;
FIG. 6 is a bottom plan view of the invention; and,
FIG. 7 is a cross-section view taken along line 7—7 in FIG. 2 illustrating the angular base of the cut out section on the upper level of the cutting board.
